(57) **CLAIM**

What is claimed is the ornamental design for a hat-attached sun shade, as shown and described.

DESCRIPTION

FIG. 1 is a perspective view of a hat-attached sun shade, showing the new design with a drape and a pair of ear coverings each in a deployed configuration;

FIG. 2 is a front elevational view thereof;

FIG. 3 is a rear elevational view thereof;

FIG. 4 is a right-side elevational view thereof, the left-side elevational view being a mirror image thereof;

FIG. 5 is a top plan view thereof;

FIG. 6 is a bottom plan view thereof;

FIG. 7 is a perspective view thereof, illustrated with only the pair of ear coverings in the deployed configuration and the drape in a stowed configuration;

FIG. 8 is a front elevational view thereof, illustrated with both the pair of ear coverings and the drape in the stowed configuration;

FIG. 9 is a rear elevational view thereof;

FIG. 10 is a right-side elevational view thereof, the left-side elevational view being a mirror image thereof;

FIG. 11 is a bottom plan view thereof; and,

FIG. 12 is a top plan view thereof.

The broken lines showing a person with a hat in the figures are included for the purpose of illustrating the invention in use, and form no part of the claimed design.
